UNITED STATES PATENT OFFICE.

FREDERICK JAMES MITCHELL, OF NEW YORK, N. Y., ASSIGNOR TO
CASPER L. COHN, OF SAME PLACE.

DISINFECTING APPARATUS.

SPECIFICATION forming part of Letters Patent No. 442,073, dated December 2, 1890.

Application filed April 11, 1890. Serial No. 347,523. (No model.)

To all whom it may concern:

Be it known that I, FREDERICK JAMES MITCHELL, a citizen of the United States, and a resident of the city, county, and State of New York, have invented certain new and useful Improvements in Apparatus for Sanitary Disinfection, of which the following is a full, clear, and exact description, reference being had to the accompanying drawings, forming part of this specification.

My invention relates to the well-known "germicide" system for the sanitary disinfection of rooms, closets, sinks, &c. In such system a solution of suitable disinfecting material—such as chloride of zinc—is applied directly to the closet-bowl or other apparatus, and a solution, preferably of thymol, is intermittently sprayed into the room or closet by means of an atomizer or similar device. An obstacle to the perfect working of this system has heretofore consisted in the difficulty experienced in supplying the disinfecting solution in the small quantity required at a constant and uninterrupted rate and of a uniform strength. The most satisfactory apparatus hitherto obtainable consisted of a receptacle containing the disinfectant in a solid form, through which water was allowed to pass on its way to the point of application, the water in its passage through the apparatus becoming impregnated with the disinfectant.

The object of my invention is the provision of an apparatus for sanitary disinfection, whereby the chloride of zinc or other disinfectant in a highly-concentrated liquid form may be substituted for the solid substance above referred to. To attain this object it is necessary that the apparatus should be of sufficient capacity to operate without attention for some time, and yet be compact and easily accessible. These requirements necessitate the use of the disinfectant in a highly-concentrated form, and consequently the rate at which it is fed must be very slow and at the same time regular and uninterrupted. For these reasons, also, an apparatus must be employed which will not become clogged by the liquid disinfectant.

To this end my invention consists in the

provision of mechanism for feeding the concentrated disinfectant regularly and at the slow rate necessarily required without clogging the apparatus, in combination with means for properly diluting the same and carrying the solution thus formed to the point of application.

It consists, further, in the combination of mechanism for producing the above result, with means for operating the atomizer or aerial disinfecter which forms part of my invention.

It consists, further, in the novel details of construction and arrangement and combination of parts, herein shown and described, and specifically pointed out in the claims.

In the accompanying drawings, Figure 1 is a view in elevation of the improved apparatus I have designed to carry out my invention. Fig. 2 is a detail sectional view of the liquid disinfectant feeding device, and Fig. 3 is a sectional view of the valve controlling the flow of the water with which said disinfectant is diluted.

Similar letters of reference are used to designate corresponding parts in all the views.

The auxiliary feeding-reservoir A is adapted to contain the liquid disinfectant, and the object thereof is to provide a sufficient supply of the disinfectant to last for some time and at the same time to maintain a constant or substantially constant head or pressure in the reservoir B, which is provided with a spout b, consisting of fibers of vitreous or mineral substances—such as spun-glass or asbestos—surrounded by an elastic packing or washer b'. A screw-threaded follower b² incloses said fibers, and the inner end thereof, which rests against said washer, is slightly concave, so that the washer will be compressed or released, thereby increasing or diminishing the circumferential pressure of the washer on said fibers as the follower is screwed in or out. A receptacle C provided with an outlet-pipe c, leading to the point to which the disinfectant is to be applied is arranged to receive the liquid which passes through spout b. A valve D, in communication with the water-supply pipe d, is arranged to deliver water into said receptacle C, where it mingles with and dilutes the

disinfectant, and the solution thus formed flows through pipe c to the desired point of application. It is essential that the rate of flow through the valve should be slow, and 5 the conical end of the valve-stem d' is therefore normally slightly off its seat, and I have obviated the clogging of the valve by sediment, &c., due to the sluggishness of the normal rate of flow through it by providing 10 mechanism for intermittently increasing the area of the valve-opening, thereby flushing the valve-passage at intervals and preventing the retention of sedimentary deposits. This result I accomplish by providing the 15 valve-stem d' with arms d^2 , rigidly connected thereto. A screw d^3 or equivalent projection is secured to said arm, and as the arm is swung around, in the manner hereinafter set forth, the projection d^3 engages with a step d^4 20 on the valve-bonnet, thereby lifting the valve-stem and increasing the area of the valve-orifice while the projection is passing over said step. By the increased flow which results therefrom the valve-passages are completely 25 flushed. As soon as the projection d^3 clears the step d^4 the valve-stem is returned to its normal position by the action of spring d^5 , which is confined between the collar d^6 and the loose collar d^7 . A packing d^8 , preferably of rubber or leather, prevents leakage 30 around the valve-stem. The valve-opening may be increased or diminished in area, as desired, by simply turning the screw d^3 in one direction or the other, so as to raise or lower 35 the valve-stem d' .

An atomizer E , of any usual construction, arranged to hold a solution of thymol or other disinfectant, is adapted to be operated by an air-compressing apparatus or pump, 40 having the cylinder F , piston f , hollow piston-rod f' , and spring f^2 , held between the piston and the upper cylinder-head. The discharge-tube e of the atomizer communicates with the apartment in which the apparatus is located, 45 and the air-supply tube e' is connected by tube e^2 with the hollow piston-rod. The lower end of the cylinder F is suitably connected, as by rod f^3 and chain f^4 , with the seat-cover or door of the closet or other movable object. 50 The cylinder F is also furnished with a projection f^5 , adapted to engage with the lever G , which is pivoted at g , and the other end of which is operatively connected by rod g' to arm d^2 .

55 The operation of the apparatus which I have just described is as follows: The auxiliary reservoir A , which is closed at the top, is filled with a concentrated disinfectant in liquid form, and the mouth thereof is inserted 60 in the reservoir B , into which the liquid flows and rises slightly above the mouth of the reservoir A , thus sealing the contents thereof to the atmosphere. As the liquid in the reservoir B is in communication with the atmosphere—as, for instance, through vent b^3 —the level of the liquid, and consequently the head 65 thereof in the reservoir B , will remain sub-

stantially constant until the contents of the reservoir A are exhausted. Under this constant head the liquid will pass through the 70 interstices between the fibers composing the spout b and the receptacle C at a very slow but regular rate, and the spout will not become clogged, because the interstices between the fibers are so minute that any sediment in 75 the liquid will not enter them. In the receptacle C the liquid disinfectant is diluted with water, which flows uninterruptedly through the valve D , and the solution thus formed flows continuously through the pipe c to the 80 point of application. When the seat-cover, door, or other object to which the chain f^4 is connected is moved in one direction, the cylinder F is moved downwardly, filling the cylinder with air, which enters through tube e' 85 e^2 and hollow piston-rod f' and enters the space beneath the piston. When the cover or seat or other object is moved back again, the spring f^2 forces the piston back to its original position, forcibly expelling the confined air through the tube e' and putting the atomizer into operation, whereby a quantity of thymol or other disinfectant contained 90 therein is sprayed into the apartment. In its downward movement the cylinder F carries 95 with it the end of lever G , which engages with the projection f^5 , and thereby swings the arm d^2 over the step d^4 . When the cylinder F moves back, it carries the arm d^2 100 back over the step. In this manner the valve D is thoroughly flushed every time the seat-cover or other object is moved.

In some cases it may be inadvisable to use the aerial disinfecter, in which case the arm d^2 may be connected directly to the object 105 by the movement of which it is desired to flush the valve. In such case, if necessary the arm d^2 may be arranged so as to be returned to its original position by a spring or weight connected thereto. The auxiliary reservoir A may also in some cases be omitted, if desired.

I do not claim herein the particular apparatus shown and described for regulating the flow of the liquid disinfectant or the particular apparatus described and shown for controlling the water-supply, as they form the 115 subject of and are separately claimed in my applications Serial No. 334,400, filed December 20, 1889, and Serial No. 343,734, filed March 120 13, 1890, respectively; but

What I do claim, and desire to secure by Letters Patent, is—

1. In a disinfecting apparatus, the combination of the reservoir B , provided with a 125 spout composed of fibers of vitreous or mineral substance, the receptacle C , provided with a suitable outlet, and the valve D , arranged to deliver water to said receptacle, substantially as and for the purposes set forth.

2. In a disinfecting apparatus, the combination of the reservoir B , provided with a spout f , composed of fibers of vitreous or mineral substance, the packing b' , the follower

b^2 , the receptacle C, provided with a suitable outlet, and the valve D, arranged to deliver water to the receptacle C, substantially as and for the purposes set forth.

5. In a disinfecting apparatus, the combination of the reservoir A, the reservoir B, having a spout composed of fibers of a vitreous or mineral substance, the receptacle C, provided with a suitable outlet, and the valve D, adapted to deliver water into said receptacle, substantially as and for the purposes set forth.

4. In a disinfecting apparatus, the combination of the reservoir A, the reservoir B, having a spout composed of fibers of a vitreous or mineral substance, the receptacle C, provided with a suitable outlet, the valve D, provided with valve-stem d' , arm d^2 , projection d^3 , step d^4 , and spring d^5 , with an atomizer, an

air-forcing apparatus adapted to operate the same, and connections between the air-forcing apparatus and the arm d^2 , substantially as and for the purposes described.

5. In a disinfecting apparatus, the combination of the reservoir A, the reservoir B, having a spout composed of fibers of a vitreous or mineral substance, the receptacle C, provided with a suitable outlet, the valve D, provided with valve-stem d' , arm d^2 , projection d^3 , step d^4 , and spring d^5 , said arm being adapted to be connected with some movable object of the nature described, substantially as and for the purposes described.

FREDERICK JAMES MITCHELL.
